UNITED STATES PATENT OFFICE

2,652,709

WASHER AND SQUEEZER EXTRACTOR

Myron W. Bowen, Niles, Mich., assignor, by mesne assignments, to Avco Manufacturing Corporation, New York, N. Y., a corporation of Delaware

Application June 29, 1949, Serial No. 102,035

4 Claims. (Cl. 68—21)

1

This invention relates to a combined washing machine and squeezer extractor of the type employing a collapsible flexible container adapted to contain washing liquid and into which the clothes are placed for a number of washing, rinsing and extracting operations, and having means to collapse the container at pre-determined points in a cycle of operations, to squeeze a major portion of the washing or rinsing liquid from the clothes contained therein.

Machines have been previously constructed employing a vacuum pump to withdraw the liquid and air from within a flexible container to create a substantial vacuum therein, thus utilizing the pressure of the atmosphere to collapse the container and thereby squeeze the liquid out of the laundry. Such a device is shown in U. S. Patent 2,472,682 issued June 7, 1949.

The primary object of this invention is to provide a combined washer and vacuum squeezer extractor having means in combination to increase the extracting ability and efficiency, such means comprising a closed chamber surrounding the flexible container into which air under pressure is pumped in combination with mechanism for withdrawing liquid and air from inside the flexible container thereby increasing the available pressure on the outside of the flexible container substantially above that of the atmosphere, but because of the differential effect of reduced pressure inside working in combination with increased pressure on the outside, a substantial squeezing of clothes is effected without excessive outside pressure.

It is a further object to provide the aforementioned means in a simple form of construction with a minimum of additional parts and control mechanisms.

It is a further object to provide in combination a means to release air pressures exceeding a predetermined amount.

Various features of my invention relate to:

Creating a vacuum or decrease in pressure within the collapsible container while simultaneously admitting air under pressure to a chamber surrounding said container, thereby effecting a substantial increase in the pressure differential between the inside and the outside of said container.

A simple and light form of construction, only, is necessary to withstand the pressures needed in the new arrangement as compared to the heavy construction that would be needed in a machine, for example, using water under pressure on the outside of the collapsible container

2

as the only means of exerting pressure for extraction. Furthermore, air, since it is both cheap and clean, is particularly suitable for the purpose in a combination mechanism withdrawing air from inside in combination with outside air pressure.

Other objects and features of novelty will become apparent from the following more detailed description and from the drawings, in which:

10 Fig. 1 is a vertical section through a combined washer and extractor of the type described showing the general arrangement and features of the present invention, including a section through the pump chamber for removing air and water from inside the collapsible container.

Fig. 2 is a cross section through the air-compressing pump chamber of the sliding-vane type used to supply air to the outside of the container.

Referring to Fig. 1, the machine comprises a flexible air and water-tight tub 10 which may be made of rubber or other suitable material, and adapted to contain a washing liquid, and into which the clothes to be washed are placed.

An agitator 11 is provided within the tub for imparting a washing action to the liquid and clothing contained therein, and a suitable transmission mechanism 12 is provided for oscillating the agitator. An opening 13 is provided at the top of the tub 10 as a means of access to the interior thereof and is sealed by a suitable air and water-tight lid 14. Means is provided for admitting water to the tub 10 through an opening (not shown) in the lid 14 by way of a water admission tube 15. Since most plumbing codes

35 require an air gap to prevent contaminated water from "backing up" in the line, such a gap is provided at 16 and separates the water admission tube 15 from an inlet hose 17 which leads from a suitable thermostatically controlled mixing valve, well known in the art and not shown.

An opening 18 is provided at the bottom of the tub 10 for removing the washing liquid and air therefrom by means of a suitable pump 19 driven by a pulley 20 on a shaft 21 through a belt 22 from a drive motor 23. The pump 19 may be of suitable construction for handling both water and air such as a flexible vane pump as shown in U. S. Patent 2,189,356, dated February 6, 1940. The drive motor 23 also drives the transmission mechanism 12 through belt 24 and pulley 25 with suitable clutch and control mechanism to drive either pump 19 through belt 22 or agitator 11 through transmission 12 as desired.

On shaft 21, driving rotor for pump 19, there is mounted another pump rotor 26 shown here

as a sliding vane compressor type (see Fig. 2) but may be of any type suitable for compressing air. An air intake 21 is provided at the intake side of pump 26 through which outside air is admitted. The compressed air from the pump 26 is forced through a conduit 28 into a chamber or wrapper 29 surrounding the tub 10 which is also air tight and made of suitable material to withstand an amount of air pressure substantially greater than that necessary to operate a safety relief valve 30 mounted thereon which comprises a plunger 31 adapted to close an opening 32 in the wrapper 29, the plunger being loaded by a spring 33. This valve is provided to release pressures exceeding that required for safe and efficient operation.

During a typical extraction period in a cycle of operations, a washing or rinsing operation is first completed by action of the agitator on the clothes and liquid contained in tub 10. After washing or rinsing is completed, the pump 19 is put in operation to pump the liquid and air from the interior of the tub 10, thus creating a substantial vacuum therein, whereby air pressure on the outside of the container causes the flexible walls of the container or tub 10 to collapse around the clothes (substantially as shown by the dotted lines in Fig. 1), and squeeze them against the agitator, and causing a substantial amount of water to be extracted from them. In the present invention, the additional pump 26 (simultaneously operated with pump 19) forces compressed air into the chamber or wrapper 29, thus building up a substantial amount of pressure over and above that of the atmosphere, and thereby appreciably increasing the extracting qualities of this type of machine.

In order to release the vacuum inside the tub 10 so that the lid 14 may be lifted and the clothes removed, a solenoid 34 in the electrical circuit is energized, which raises a plunger to which a valve seat 35 is attached, thereby clearing the water inlet opening in the lid 14 so that air may enter the tub 10, expanding it to its normal position against the wrapper 29 as shown. This particular type of vacuum release along with a combined water inlet is more particularly shown and described in co-pending application Serial No. 33,184, filing date June 15, 1948, now U. S. Patent No. 2,535,226.

To release the pressure of the compressed air between the tub 10 and the wrapper 29, a solenoid 36 is energized, preferably at the same time as solenoid 34, by closing a switch 37 in the electrical circuit causing the plunger 31 to be pulled away from the opening 32 in the wrapper 29 against the bias of the spring 33 thereby allowing the air to escape.

It should be here noted that if, at any time during an extraction period, the pressure inside the wrapper 29 exceeds that necessary for safe and efficient operation, the spring 33 will become slightly compressed allowing the plunger 31 to be pushed away from the opening 32 so that the excess air pressure in the chamber between the wrapper and the tub will be allowed to escape.

While one embodiment of my invention is here illustrated and described, it is not intended to be limited to that particular embodiment otherwise than by the terms of the appended claims.

What I claim is:

1. A washing machine comprising a flexible

liquid and airtight element, a closed chamber surrounding said element, said element having an opening through which laundry may be inserted and removed, an air and watertight closure for said opening, means for agitating laundry within said element, driving means for said agitating means, said liquid and airtight element having side walls substantially wholly surrounding said laundry and said agitating means, a pump for withdrawing liquid and air from said element to create a substantial vacuum therein, driving means for said pump, a second pump operable simultaneously with said first pump for supplying air under pressure into said chamber surrounding said element to squeeze liquid from said laundry by pressure exerted against the outer surface of said element, and driving means for said second pump.

2. A washing machine comprising a flexible liquid and airtight element, a closed chamber surrounding said element, said element having an opening through which laundry may be inserted and removed, an air and watertight closure for said opening, means for agitating laundry within said element, said liquid and air tight element having side walls substantially wholly surrounding said laundry and said agitating means, a driven shaft and driving means therefor, a pump on said driven shaft for withdrawing liquid and air from said element to create a substantial vacuum therein, and a second pump on said driven shaft for simultaneously supplying air under pressure into said chamber surrounding said element to squeeze liquid from said laundry by pressure exerted against the outer surface of said element.

3. A washing machine comprising a flexible liquid and airtight element, a closed chamber surrounding said element, said element having an opening through which laundry may be inserted and removed, an air and watertight closure for said opening, means for agitating laundry within said element, said liquid and airtight element having side walls substantially wholly surrounding said laundry and said agitating means, means for withdrawing the liquid and air from said element to create a substantial vacuum therein, means for simultaneously supplying air under pressure into said chamber surrounding said element to squeeze liquid from said laundry by pressure exerted against the outer surface of said element, and means mounted on said chamber to release the pressure in said chamber surrounding said element.

5. The combination as in claim 3 having means to release the vacuum inside said element.

MYRON W. BOWEN.
